(57) **CLAIM**

The ornamental design for an access control gate as shown and described.

DESCRIPTION

FIG. 1 is a front view of an access control gate showing my new design in a first configuration;

FIG. 2 is a rear view thereof;

FIG. 3 is a rear view showing the access control gate in a second configuration;

FIG. 4 is a front view showing the access control gate in a third configuration; and,

FIG. 5 is a front view showing the access control gate in the second configuration.

The broken lines indicated environment and portions of the access control gate and form no part of the claimed design.

1 Claim, 5 Drawing Sheets
